US0D1001083S

(12) **United States Design Patent** (10) Patent No.: **US D1,001,083 S**
(45) Date of Patent: ** *Oct. 10, 2023

(54) **FUNCTION MODULE**

(71) Applicant: **Beckhoff Automation GmbH, Verl (DE)**

(72) Inventors: **Frank Greiser, Rheda-Wiedenbrück (DE); Hans Beckhoff, Verl (DE)**

(*) Notice: This patent is subject to a terminal disclaimer.

(**) Term: **15 Years**

(21) Appl. No.: **35/515,083**

(22) Filed: **May 18, 2022**

(80) **Hague Agreement Data**

Int. Filing Date: **May 18, 2022**

Int. Reg. No.: **DM/223141**

Int. Reg. Date: **May 18, 2022**

Int. Reg. Pub. Date: **Sep. 9, 2022**

(30) **Foreign Application Priority Data**

Nov. 19, 2021 (EM) 008768477-0020

(51) **LOC (14) Cl.** **13-03**

(52) **U.S. Cl.**

USPC **D13/162.1**

Primary Examiner — Lauren D McVey

(57) **CLAIM**

The ornamental design for the function module, as shown and described.

DESCRIPTION

1. Equipment for distribution of electric power

FIG. 1.1: Perspective front view of a function module;

FIG. 1.2: Perspective back view of the function module;

FIG. 1.3: Right view of the function module;

FIG. 1.4: Front view of the function module;

FIG. 1.5: Back view of the function module;

FIG. 1.6: Top view of the function module;

FIG. 1.7: Rear view of the function module;

FIG. 1.8: Left view of the function module;

1 Claim, 8 Drawing Sheets
